UNITED STATES PATENT OFFICE

2,444,376

LIPSTICK CONTAINER

Donald A. Seaver, West Cheshire, Conn., assignor
to Scovill Manufacturing Company, Water-
bury, Conn., a corporation of Connecticut

Application September 2, 1944, Serial No. 552,473

17 Claims. (Cl. 206—56)

1

This invention relates to certain improvement in dispensing containers for lipstick, eyebrow pencil and similar soft pasty cosmetics.

Particularly the invention relates to a type of container in which the cosmetic is supported in a carrier which is elevated and retracted within a casing by rotating one member relative to another member, and which type of container is generally known as a swivel type of lipstick container.

This invention pertains particularly to the construction of the pin member that is employed for elevating the carrier cup within the container coincident with rotating one part of the container relative to another part. Heretofore, the pins for this type of article have been generally made from screw machine products or headed pins which have been more or less expensive to manufacture, requiring a difficult riveting operation in assembling the pin to the carrier cup and presenting only a relatively small surface area of the pin head to the side edge of a helical groove through which the pin head operates for elevating and retracting the carrier cup within the container.

It is one of the objects of this invention to make the elevator pin by blanking it out of flat sheet material providing for a longitudinal blank having lugs at the opposite ends inclined to the longitudinal axis of the blank such that the lugs will conform to the pitch of the helix when folded at right angles to said blank.

Another object of this invention is to fabricate the elevator pin from a flat blank of sheet material so that it can be readily assembled and disassembled from the carrier cup, thus permitting the carrier cup to be removed from the casing and salvaged in case any part of the casing is found defective.

With these and other objects in view, the invention consists in certain novel features of construction, combination and arrangement of parts, as will be more fully disclosed in connection with the accompanying drawing and as set forth in the annexed claims.

In the drawing:

Fig. 1 is generally an elevational view of the interior part of the swivel type lipstick container with the outside shell in section and the cover member omitted.

Fig. 2 is an enlarged fragmentary sectional view taken at 90° to the view of Fig. 1 and showing a side elevational view of the operating pin.

Fig. 3 is a transverse sectional view taken substantially along the line 3—3 of Fig. 2.

2

Fig. 4 is a perspective view of the carrier cup and the operating pin in detached relationship.

Fig. 5 is a development plan view of the pin blank in its initial flat state as it appears when blanked out from a piece of sheet material.

Fig. 6 is an upper edge view of the operating pin as it appears in its finished folded state.

Fig. 7 is a front elevational view of the same.

Fig. 8 is an end view of Fig. 7 as it appears from the right.

Fig. 9 is a view similar to Fig. 3 except showing a modification wherein the lugs of the elevator pin are so formed as to present a tensional factor in the recess wherein they operate.

Fig. 10 is a blank from which a further modified form of pin may be made, and

Fig. 11 is a front elevational view of the modified form of the pin of Fig. 10.

Referring now to the drawing in which like reference numerals refer to corresponding parts throughout the several views: the numeral 10 refers generally to a dispensing container with the cover member omitted. The container comprises an outside tubular shell casing 11 and an inside shell 12 rotatably mounted within said casing 11. Disposed between the outside shell casing 11 and the inside shell 12 and adapted to be retained and carried by the outside shell casing 12 is a spiral sleeve 13 having a helical slot or groove 14 extending from end to end thereof.

The base or lower end of the inside shell 12 is provided with an enlarged integral head 15 having a diameter slightly larger than the diameter of the outside shell casing 11 and preferably provided with formed circumferential ribs to present a better gripping surface to facilitate in the operation of the device. Removed from the open end of the inside shell 12 is an outwardly knurled bead 16 for holding the spiral sleeve 13 within confined quarters. The upper end of the outside shell casing 11 is spun over as at 17 to cover up the raw edge of the inside shell 12 and present a better finished appearance at the open end of the container 10.

Mounted to slide within the inside shell 12 is a carrier cup or elevator member 18 in which a cosmetic stick 19 is held. The inside shell is provided with a longitudinal slot 20 extending substantially the entire length thereof.

The purpose of this invention is to provide a much cheaper and simpler pin construction which cooperates with the mechanism generally employed in swivel type lipstick containers for the purpose of elevating and retracting the carrier cup therewithin. To this end the elevator pin,

generally indicated by the numeral 21, is preferably made from a predetermined shaped flat blank 22 as illustrated in Fig. 5 and such as can be cut and blanked out from flat sheet material. The blank 22 comprises a longitudinal body part 23 having biased portions 24 at opposite ends thereof that constitute the lug parts of the finished pin 21. The biased portions 24 are preferably made somewhat wider than the width of the body part 23 of the blank 21 for reasons as will appear later.

The body part of the blank 22 is first formed up about a center fold line as represented by the dot-and-dash line at 25 so that the body portion of the blank is folded flat upon itself into two thicknesses of material and constitutes the body part 26 of the pin 21. The biased or lug portions 24 are next bent substantially at right angles in opposite directions along fold lines 27 at the opposite ends of the body portion 26 proper. The lugs 24 are finally formed into an arcuate shape as shown in Fig. 6 so as to conform substantially to the outside diameter of the inside shell 12.

The carrier cup is provided with a rectangular opening 28 through its side wall, the axis of which is parallel to the cup axis and of a width comparable to the double material thickness of the pin body part 26.

In assembling the container parts together the spiral sleeve 13 will first be slipped over the inside shell 12 and confined between the head 15 and the knurled bead 16. The carrier cup 12 will next be dropped into the interior of the inside shell with its rectangular side wall opening 28 thereof aligned with the longitudinal slot 20 of the inside shell and also with some portion of the helical slot 14 of the spiral sleeve 13. The sheet metal pin 21 in its complete form, as shown in Figs. 6 and 7, will then be aligned with the three aligned openings 14, 20 and 28 and inserted through the opening 28 of the carrier cup 12 until the lugs engage the outer wall of the inside shell 12. Then the outside shell casing 11 is finally slipped over the assembled parts 12, 13, 14 and 21 and completes the assembly, after which a cover, not shown, may be slipped over the outside shell to complete the unit. The inner wall of the outside shell casing 11 will retain the elevator pin 21 in assembled position and cause the biased lugs 24 thereof to operate within the helical slot 14.

The fact that the carrier cup rectangular opening 28 is disposed in a vertical position serves to position the body part 26 of the pin 21 in a position where the narrower edge of the double material thickness of said body part is disposed in the carrier cup and thus presents the minimum thickness of the operating pin to the stick material 19 when assembled there in place. Also the angular position of the lugs 24 as formed relatively to the body part of the blank 22 and the fact that these lugs are bent along fold lines at right angles to blank axis will dispose them in the proper angular position to be received and operated within the helical slot 14. The width of the lugs 24, best shown in Fig. 5, is made slightly wider than the body part proper 26 of the blank 22 so that the transverse dimensions of the lugs 24 will be substantially equal to the transverse width of the helical slot and of a character to provide an easy slidable movement therethrough with as little play as possible.

While preference has been given to a rectangular opening 28 with its longitudinal axis parallel to the cup axis to maintain the body part 26 of the pin 21 in the desired position to the cup and

the lugs 24 to the helical slot 14, it can be seen that a round opening 28 of a size to accommodate the width of the pin body part 26 can be provided in the cup 12 and operate effectively as well. In this latter case, however, the desire to have the pin body part disposed in a plan substantially parallel to the cup axis will be maintained by reason of the lugs engaging in the helical slot 14 and the fact that they are substantially of a width to fill the transverse width of said slot 14.

In the form shown in Figs. 1, 2 and 3 the thickness of the blank 22 from which the pin 21 is fabricated is not quite as thick as the material from which the spiral sleeve 13 is made. Therefore, the lugs 24 do not completely fill the depth of the helical slot 14 within which it operates, such as shown in Fig. 3. In Fig. 9 there is shown a modification wherein the lugs 24a are formed in an arc of considerably less radius than the radius of the inside shell 12 such that the particular arcuate formation of the lugs will present a tensioning factor between the adjacent walls of the inside shell 11 and outside shell casing 12 and act to resist the carrier cup 12 from being forced back into the container 10 when applying the cosmetic material.

In folding a flat blank of material upon itself such as to form the body part 26 of the pin 21, as shown in Fig. 6, there is always a natural tendency of the material to expand edgewise beyond the normal width of the blank out of which it is formed at the point where the severest fold is made. To overcome this tendency of the material to expand edgewise, the blank 22 may be cut out as at 29, in its opposite edges and symmetrical to the center fold line 25 so that, when the blank is folded upon itself, the leading edge 30 will be slightly less in width than the normal width of the double thickness of the body part 26 of the pin and present a somewhat leading tapering end to facilitate the assembly of the pin 21 and particularly its entrance through the opening 28 in the carrier cup.

It is also within the purview of this invention to make a pin 21b wherein there is only one thickness of material constituting the body part of the pin proper. This modification is shown in Figs. 10 and 11. The pin 21b as shown in Fig. 10 is initially shown as formed from a blank 22b comprising a straight body part 26b of single sheet thickness and an offset lug 24b at one end thereof. The lug 24b similar to the lugs of the form of Fig. 5 is adapted to be bent along the fold line 27b at right angles to the longitudinal axis of the blank 26b, the lug 24b preferably being arcuate as shown in Fig. 11 to conform to the diameter of the inside shell 12. Also if desirable this operating pin with a single type of lug may have its lug formed in an arc of a smaller radius so as to function in a like manner to the lugs described in connection with the modification shown in Fig. 9.

While the invention embodying the pin construction has been shown and described in several different forms for use in swivel type of lipstick containers, it will be understood that other changes and variations may be made in the specific constructions shown and described and applicable to other types of containers without departing from the scope of the invention as defined in the appended claims.

I claim:

1. In a cosmetic holder of the character described, an outer casing, an inner tubular member rotatable in said casing and having a longitudinal slot, means associated with said outer

casing providing for a helical slot, a carrier cup for receiving a cosmetic material and provided with a narrow elongated rectangular wall opening longitudinally arranged and parallel to the axis of the cup, the improvement which consists of an operating pin constructed from a blank of flat thin sheet material and comprising a flat body part and an elongated lug bent on a line at right angles to the axis of the body part and disposed in a biased angular position relative to its connected end with the body part, said body part being positioned in the wall opening of said carrier cup and extending through said casing longitudinal slot, said wall opening serving to hold said body part in a plane parallel to the axis of said holder so as to present only a narrow edge of the body part to any material telescoped into said carrier cup, and the biased angular position of said elongated lug causing it to lie within and conform to the angular pitch of said helical slot and adapted to slidably operate therein.

2. In a cosmetic holder of the character described, an outer casing, an inner tubular member rotatable in said casing and having a longitudinal slot, means associated with said outer casing providing for a helical slot, a carrier cup for receiving a cosmetic material and provided with a narrow elongated rectangular wall opening longitudinally arranged and parallel to the axis of the cup, the improvement which consists of an operating pin constructed from a blank of flat thin sheet material and comprising a flat body part and an elongated lug of greater transverse width than said body part, said lug bent on a line at right angles to the axis of the body part and disposed in a biased angular position relative to its connected end with the body part, said body part being positioned in the wall opening of said carrier cup and extending through said casing longitudinal slot, said wall opening serving to hold said body part in a plane parallel to the axis of said holder so as to present only a narrow edge of the body part to any material telescoped in said carrier cup, and said lug by reason of its increased width and biased angular position relative to the body part being disposed in said helical slot and substantially filling the cross width of said helical slot and adapted to slidably operate therein.

3. A cosmetic holder as defined by claim 1 wherein the lug of said operating pin in addition to being bent substantially at right angles to said body part is formed in an arc conformable to the outside diameter of said inner tubular member.

4. A cosmetic holder as defined by claim 1 wherein the lug of said operating pin in addition to being bent substantially at right angles to said body part is further formed in an arc less than the outside diameter of the inner tubular member to thereby create a frictional factor between the outer casing and inner tubular member when said lug is operating within said helical slot.

5. In a cosmetic holder of the character described, an outer casing, an inner tubular member rotatable in said casing and having a longitudinal slot, means associated with said outer casing providing for a helical slot, a carrier cup for receiving a cosmetic material and provided with a narrow elongated rectangular wall opening longitudinally arranged and parallel to the axis of the cup, the improvement which consists of an operating pin constructed from a blank of flat thin sheet material and comprising an elongated flat body part of double material thickness joined together at one end by a folded portion, a pair of lugs oppositely extending from the other end of said body part substantially at right angles thereto and disposed in a biased angular position relative to their connected ends with the body part, said body part of double thickness positioned in the wall opening of said carrier cup and extending through said casing longitudinal slot, said wall opening serving to hold said body part in a plane parallel to the axis of said holder so as to present only a narrow edge of double material thickness of said body part to any material telescoped into said carrier cup, and the biased angular position of said opposed lugs causing them to lie within and conform to the angular pitch of said helical slot and adapted to slidably operate therein.

gated flat body part of double material thickness joined together at one end by a folded portion, a pair of lugs oppositely extending from the other end of said body part substantially at right angles thereto and disposed in a biased angular position relative to their connected ends with the body part, said body part of double thickness positioned in the wall opening of said carrier cup and extending through said casing longitudinal slot, said wall opening serving to hold said body part in a plane parallel to the axis of said holder so as to present only a narrow edge of double material thickness of said body part to any material telescoped into said carrier cup, and the biased angular position of said opposed lugs causing them to lie within and conform to the angular pitch of said helical slot and adapted to slidably operate therein.

6. In a cosmetic holder of the character described, an outer casing, an inner tubular member rotatable in said casing and having a longitudinal slot, means associated with said outer casing providing for a helical slot, a carrier cup for receiving a cosmetic material and provided with a narrow elongated rectangular wall opening longitudinally arranged and parallel to the axis of the cup, the improvement which consists of an operating pin constructed from a blank of flat thin sheet material and comprising an elongated flat body part of double material thickness joined together at one end by a folded portion, a pair of lugs oppositely extending from the other end of said body part substantially at right angles thereto, and disposed in a biased angular position relative to their connected ends with the body part, the transverse width of said lugs being of a width greater than said body part, said body part of double thickness being positioned in the wall opening of said carrier cup and extending through said casing longitudinal slot, said wall opening serving to hold said body part in a plane parallel to the axis of said holder so as to present only a narrow edge of double material thickness of said body part to any material telescoped into said carrier cup, and said lugs by reason of their increased width and biased angular position relative to said body part being disposed in said helical slot and substantially filling the cross width of said helical slot and positioned in conformity to the angular pitch thereof and adapted to slidably operate therein.

7. A cosmetic holder as defined by claim 5 wherein the opposed lugs of said operating pin in addition to being bent substantially at right angles to said body part are formed in an arc conformable to the outside diameter of said inner tubular member.

8. A cosmetic holder as defined by claim 5 wherein the opposed lugs of said operating pin in addition to being bent substantially at right angles to said body part are formed in an arc less than the outside diameter of the inner tubular member to thereby create a frictional factor between the outer casing and inner tubular member when said lugs are operating within the helical slot.

9. As an article of manufacture, an operating pin for use with the carrier cup of the conventional swivel type lipstick container, said pin made from a single developed blank of flat sheet material and comprising an elongated flat body part of uniform width and lying in a single plane, and an integral elongated flat lug also of uniform width and bent on a line perpendicular to the longitudinal axis of said body part and lying

in a plane substantially normal to the plane of said body part, said lug also being in a biased angular position relative to the plane of said body part.

10. An article of manufacture as defined by claim 9 wherein the transverse width of said lug is of slightly greater width relative to the transverse width of said body part.

11. An article of manufacture as defined by claim 9 wherein the lug is of arcuate shape along its longitudinal axis.

12. An as article of manufacture, an operating pin for use with the carrier cup of the conventional swivel type lipstick container, said pin made from a single developed blank of flat sheet material and comprising an elongated body part of uniform width of double material thickness joined by a folded portion at one end and lying in a single plane, and a pair of elongated lugs integral with the other end of the body part and bent oppositely from the plane of the body part on a line perpendicular to the body part and lying in a plane substantially normal to the body part, said lugs also being in a biased angular position relative to the plane of said body part.

13. An article of manufacture as defined by claim 12 wherein the opposed lugs are of slightly arcuate formation along their longitudinal axis.

14. An article of manufacture as defined by claim 12 wherein the folded portion at one end of the body part is of slightly less width relative to the transverse width of said body part.

15. A pin blank for a lipstick container consisting of a single piece of thin flat sheet material adapted to be formed up into an operating pin for the carrier cup of said container, said blank comprising a longitudinal straight body part of uniform width its entire length and presenting opposite upper and lower parallel edges, the upper edge being longer than the lower edge and an integral single lug also having parallel edges and extending from that end of the body part having the longer edge, said lug being axially shorter than the axial length of said body part and of a transverse width greater than the

transverse width of said body part and positioned on an upwardly directed obtuse angle relative to the longitudinal axis of said body part.

16. A pin blank for a lipstick container consisting of a single piece of thin flat sheet material adapted to be formed up into an operating pin for the carrier cup of said container, said blank comprising an elongated body part of uniform width its entire length and presenting upper and lower parallel edges, and a pair of oppositely extending lugs having parallel edges and one only extending from each opposite end of said body part, the transverse width of said lugs being greater than the transverse width of said body part, and each of said lugs positioned on an outwardly directed obtuse angle relative to the longitudinal axis of said body part.

17. A pin blank as defined by claim 16 wherein in the opposite parallel edges of said blank are formed with oppositely cut-in recesses substantially at a mid position relative to the length of the body part and of a length approximating the double thickness of the blank.
